Wallace Wiley

Attorney

UNITED STATES PATENT OFFICE.

ERNEST L. BAILEY, CHARLES H. SCOTT, AND WALLACE WILEY, OF LOOKOUT,
KENTUCKY.

MINE DOOR.

Application filed July 3, 1924. Serial No. 724,096.

To all whom it may concern:

Be it known that we, ERNEST L. BAILEY, CHARLES H. SCOTT, and WALLACE WILEY, citizens of the United States, residing at 5 Lookout, in the county of Pike and State of Kentucky, have invented certain new and useful Improvements in Mine Doors; and we do hereby declare the following to be a full, clear, and exact description of the invention, such as will enable others skilled in the art to which it appertains to make and use the same.

This invention relates to new and useful improvements in doors and operating means 15 therefor, and particularly to doors used in mines.

One object of the invention is to provide a device of this character wherein the door is normally maintained in closed position, 20 but is capable of being pushed into open position by the locomotive, and closing after the train has passed.

Another object is to provide a door of this character which is capable of being opened 25 from either direction, and which has means against which the locomotive is adapted to strike, to cause the door to swing open, and whereby the door is protected from excessive wear.

30 Other objects and advantages will be apparent from the following description when taken in connection with the accompanying drawing.

In the drawing:

35 Figure 1 is a cross sectional view through a mine tunnel, showing the door in closed position.

Figure 2 is a horizontal sectional view on the line 2—2 of Figure 1, the door being 40 in open position.

Referring particularly to the accompanying drawing, 10 represents the railway, in the tunnel 11, of a mine, while 12 represents the doorway frame of the tunnel. 45 Hinged to one of the uprights of the doorway frame 12 is the horizontally swingable door 13, said door extending across the railway, and completely closing the doorway, except for the small space below the door, 50 above the rails. Rotatably supported in a horizontal position, in a recess 14, in the lower face of the transverse members of the doorway frame, and adjacent the hinged end of the door, is a grooved wheel 15. Suspended from the roof of the tunnel, at each

side of the doorway, and adjacent the hinged end of the door, are the vertically disposed grooved wheels 16 and 17, respectively. Secured to the upper edge of the door 13, at a point approximately midway of the length thereof, is one end of a cable 18, the same passing around the opposite side of the wheel 15, and thence over the wheel 16, with a weight 19 secured to its pendent end. A similar cable is secured to the upper edge 60 of the door, adjacent the point of attachment of the cable 18, as shown at 20, said cable 20 engaging around the near side of the wheel 15, and thence through the pulley 17, and having a weight 21 secured to its pendent 65 end.

Secured to each side face of the door 13, and extending longitudinally thereof, is an outwardly bowed bumper bar 22, against which the locomotive is adapted to strike, 70 to push the door into open position, said bar being engaged by each car, as the car passes through the doorway, whereby the door is maintained in open position until the last car of the train has passed through 75 the doorway. A handle 23 is secured to the lower portion of the door, on each side, to permit manual opening and closing of the door.

As the door is swung in one direction one 80 of the cables will exert a pull on the weight carried by the other end thereof, with the result that said weight will be elevated. When the door has been moved until it is beyond the ends of the ties 24, the other cable is pulled to a slight degree, with the result that when the last car has passed out of contact with the door, the combined action of the descent of the two weights will 85 impart an initial closing impulse to the door, thus insuring the proper closing thereof.

What is claimed is:

1. A mine tunnel closure including a doorway, a door mounted for swinging movement in the doorway, car engaging bumpers on the opposite sides of the door, and weights for yieldably holding the door in closed position. 100

2. A mine tunnel closure including a doorway, a door mounted for swinging movement in the doorway, car engaging bumpers on each side of the door, a horizontal grooved wheel mounted in the upper side of the doorway, vertical grooved wheels at op- 105 110

- posite sides of the doorway at the supported side of the door, and weight carrying cables connected with the door and engaged with the wheels.
- 5 3. In a mine tunnel closure, a doorway, a horizontal grooved wheel mounted in the upper portion of the doorway, a door hinged in the doorway for swinging movement in either direction, vertically disposed grooved 10 wheels suspended from the ceiling of the tunnel at opposite sides of the doorway and adjacent the hinged side of the door, cables connected to the door and engaged around

the first wheel and extending in opposite directions longitudinally of the tunnel and 15 over the second pulleys respectively, and weights carried by the pendent ends of the cables.

In testimony whereof, we affix our signatures, in the presence of two witnesses.

WALLACE WILEY.
ERNEST L. BAILEY.
CHAS. H. SCOTT.

Witnesses:

R. E. STEPHENSON,
R. H. DICKERSON.
